DOOR HOLDER

Benjamin S. Bernhard, Boston, Mass., assignor to
the American Hardware Corporation, New
Britain, Conn., a corporation of Connecticut

Application September 25, 1940, Serial No. 358,193

6 Claims. (Cl. 16—49)

This invention relates to improvements in friction door holders.

Friction door holders employing the resistance offered by a shoe sliding within a track to hold a door in any desired angular relation with the header have not heretofore fully or efficiently utilized the surface available for such resistance. The shoe, which is frictionally slideable with respect to the track, is customarily held within a track of generally channel section, and either the bottom or both sides thereof have been utilized as friction surfaces. The prior art devices have usually employed springs, wedges, etc., for expanding the shoe and such expanding means have acted at most on two opposed friction surfaces.

It is an object of my invention to provide a substantially improved friction door holder.

It is another object to provide improved friction holding means.

The invention further contemplates provision of improved means for quietly buffering shoe travel in a door-holding device of the character indicated.

Other objects and various features of the invention will be hereinafter pointed out or will become apparent to those skilled in the art.

In the drawing which shows, for illustrative purposes only, a preferred embodiment of the invention—

Fig. 1 is a plan of my door holder incorporated with a door and header, the door being shown in its extreme open position;

Fig. 2 is an enlarged vertical sectional view of the door holder shown in Fig. 1, the parts being shown in their respective relationships for a closed door; and

Figs. 3 and 4 are further enlarged sections taken substantially in the planes 3—3 and 4—4, respectively, of Fig. 2.

Referring to Fig. 1 my improved door-holding means comprises generally a track 5 of generally channel section and mortised, in the embodiment shown, within the upper edge of the door 6. Slidably mounted within the channel 5 is a shoe member, designated generally as 7, pivotally supporting one end of an arm 8. The other end of the arm 8 is pivotally anchored to the door header 9 by suitable means 10. In the position shown in Fig. 1 the door 6 is open to its maximum extent and is prevented from exceeding this maximum by suitable buffer means, designated generally as 11. Another buffer 12, similar to the buffer 11, may be provided if desired at the other end of the track 5. It will be clear

that, when the door is shut, the shoe 7 will be displaced along the track 5 and will abut the buffer 12 (when provided).

More specifically, and viewing Figs. 2 and 3, the shoe 7 preferably includes a main body member or slide 13, easily fitting within track 5 and sliding along beneath and retained by the upper flanged or shouldered portions 14 thereof. An arm 8 is carried by the slide 13 and is pivotally connected thereto by the stud 15, which has a flanged portion received in a correspondingly countersunk receiving portion of the arm 8 and is permanently secured in place by such means as being headed over the inside of a countersunk portion 16 (Fig. 3) of the slide 13. The downwardly extending end portions 13a of the slide 13 will be understood to be a rigid means contributing to hold the separate parts of the shoe 7 in unit-handling relation and for abutment of the shoe with a buffer stop 11 or 12. A washer 17 and guide plate 18 are shown interposed between the arm 8 and slide 13. These parts assure a free pivoting of the arm with respect to the slide and guide the slide in such straight alignment within the track 5 that jamming or uneven wear will be minimized, as will be understood. Lobes 19 on the guide member 18 may fit in corresponding lobe-receiving holes or recesses on the slide member 13, to lock one member to the other.

Frictional resistance to the passage of the shoe 7 within the channel 5 results from an urging of friction pieces 20 expandable outwardly against the side walls 21 of the channel and of a friction piece 22 movable downwardly against the bottom 23 thereof. This urging downwardly and outwardly of said friction pieces may be obtained as follows:

Downward pressure, derived from an adjusting screw 24 threaded within the stud 15, is transmitted to a plate 26, as by the flanged stud 25, the flanged portion of which should be larger than the adjusting screw diameter, so that, upon retraction of the screw 24, the shoe unit 7 may still remain in unit handling relationship. The plate 26 serves to distribute pressure substantially uniformly over a block 27 of rather resilient material, such as rubber or the like. The resilient block 27 fits within two angle strips 28 and, when compressed by a downward thrust of the adjusting screw 24 upon the plate 26, will apply both downward and outward pressure to angle strips 28, as will be understood from the near-fluid properties of a relatively resilient material, such as rubber, under such conditions. It will be further observed that the downward

and outward thrusts thus exerted on the angle strips 28 will be substantially uniformly distributed over the respective friction pieces 20 and 22, thereby increasing the resistive frictional effort the shoe 7 may offer to any sliding tendency. It will be understood that a backing-up of the adjusting screw 24 will serve to relieve friction-piece pressure on the walls of the track and to render the shoe more readily slideable, as may be desired.

The plate 26, resilient block 27, angle strips 28 and friction pieces 20 and 22 are all substantially of a length determined by the downwardly extending end portions 13^a of the slide 13. The end portions 13^a thus serve to hold the parts embraced by slide 13 in unit-handling relationship.

In the form shown stopping means for the shoe comprises ultimately a block 29, through which mounting screws 30 may be inserted and thus anchor both the track 5 in its mortised position within the door or header, as the case may be, and the block 29 within the channeled portion of track 5.

In accordance with another feature of my invention I provide an improved type of buffering means 11 or 12, held within the track 5 and between the shoe and one of the stopping blocks 29. My buffer assembly preferably includes a generally U-shaped channel member 31, inverted with respect to the channel of the track 5 and fitting frictionally therein. Slidable within the channel 31 is a generally U-shaped or cup member 32, which serves as a guide for traveling parts within the buffer stop. For quiet, resilient operation of the buffer I prefer to employ blocks 33 of relatively resilient material, such as rubber, for direct abutment with the shoe portion 13^a. This resilient block is carried on the guide member 32 and so held by a necked-knob portion 34 of the block 33, passed through an opening in the guide 32. Heavy shocks of the shoe against a buffer are taken up primarily by such resilient means as a spring 35, which is shown spacing the resilient block 33 from the fixed stopping block 29. It will be observed that the knob 34 of the resilient block 33 may be designed so as closely to fit the inside of the coil spring 35 and thus serve as a centering means for the spring in order to obviate any possible danger of a turn of the spring 35 catching an edge of the guide member 32 and making undesirable noise. It will also be noted that the buffer unit may be held in unit-handling relation within the track 5 by provision of a pair of indented or swaged-in portions 36 on the channel member 31. Such provision will prevent spring compression from displacing the guide member 32, and hence the buffer moving parts, any further than substantially the end of the channel 31.

I have indicated above that provision of the buffer 12 may be desirable. This may be when noise elimination is of the utmost importance. It will be seen that when the door is almost closed there is very little displacement of the shoe 7 within the track 5 for a given opening of the door. It is apparent, then, that very little resistance to opening or shutting will be offered when the door is so nearly closed. Inclusion of the additional buffer 12 may serve to provide the needed additional resistance by permitting the shoe 7 to abut the buffer 12 just before door closes and thus to deaden shock and noise upon closing.

It will be observed that I have provided a substantially improved type of shoe offering frictional resistance to its passage within a track—

a shoe which utilizes efficiently all the inside surfaces of a channel or generally U-shaped track and at the same time one in which pressure is distributed substantially uniformly throughout all the friction surfaces. In addition my improved buffer incorporates means substantially to eliminate noise and lengthen the life of the parts.

While the invention has been described in considerable detail and preferred forms illustrated in connection with a door and header, it is by no means intended so to be limited; and it is to be understood that various changes and modifications may be made within the scope of the invention as defined in the appended claims.

I claim:

1. In a device of the character indicated, a track of generally channel section and having inwardly directed flanges at the open side of the channel, a shoe slideable within said channel section of said track and having a body member for sliding coaction with the inner shoulder portions of said inwardly directed flanges, means incorporated with said shoe for offering variable frictional resistance to the passage of said shoe within said track, said means comprising friction pieces in flat abutment with the adjacent surfaces of said channel track, a pair of angle strips each engaging two of said friction pieces, a block of resilient material seated within said angle strips, a stud fixed to said shoe body member and projecting above said shoe for support of an external member to be borne by said shoe, an adjusting screw threaded within said stud, and means in abutment with said adjusting screw for distributing pressure substantially uniformly to the remaining surface of said block of resilient material.

2. In a device of the character indicated, a track of generally channel section and having inwardly directed flanges at the open side of the channel, a shoe slideable within said channel section of said track and having a body member for sliding coaction with the inner shoulder portions of said inwardly directed flanges, means incorporated with said shoe for offering variable frictional resistance to the passage of said shoe within said track, said means comprising friction pieces in flat abutment with the adjacent surfaces of said channel track, a pair of angle strips each engaging two of said friction pieces, a block of resilient material seated within said angle strips, a stud fixed to said shoe body member and projecting above said shoe for support of an external member to be borne by said shoe, an adjusting screw threaded within said stud, and means in abutment with said adjusting screw for distributing pressure substantially uniformly to the remaining surface of said block of resilient material, said sliding body member having downwardly extending end portions serving to confine said friction pieces, said angle strips, said resilient block, and said means for distributing pressure substantially uniformly to said resilient block.

3. In a device of the character described, a channel member having parallel sides, a friction block slideable in said channel and including friction pieces at the opposite sides thereof, another friction piece at the bottom thereof, said side and bottom pieces bearing against the sides and bottom of said channel member, and a manually adjustable means to force said pieces against the side walls and bottom wall of said channel member to increase the pressure of said

pieces on all three walls of said channel to control at will the frictional resistance to the sliding of said block in said channel.

4. In a device of the character described, a channel member having parallel sides, a friction block slideable in said channel and including friction pieces at the opposite sides thereof, another friction piece at the bottom thereof, said side and bottom pieces bearing against the sides and bottom of said channel member, a manually adjustable means to force said pieces against the side walls and bottom wall of said channel member to increase the pressure of said pieces on all three walls of said channel to control at will the frictional resistance to the sliding of said block in said channel, said manually controllable means including a block of resilient material for transmitting pressure to said side and bottom pressure pieces.

5. In a device of the character indicated, a channel member having turned in flange means defining a longitudinally extending slot opening into said channel member, friction means within said channel member and engaging all of the

walls thereof and the under surface of said flange means, said friction means including a block of resilient rubber-like material, and means for stressing said block of resilient rubber-like material for the purpose set forth, an arm, and pivotal means extending through said slot and connecting said arm and friction means.

6. In a device of the character indicated, a channel member having turned in flange means defining a longitudinally extending slot opening into said channel member, friction means within said channel member and including friction pieces engageable with the walls of said channel member and with said flange means, said friction means including a block of resilient rubber-like material located between said friction pieces for resiliently urging all of said friction pieces into frictional engagement with said walls and flange means, means varying the stress on said block of rubber-like material to vary the friction force on all of said friction pieces, an arm, and pivot means extending through said slot and pivotally connecting said arm and friction means.

BENJAMIN S. BERNHARD.
